US0D1003238S

(12) **United States Design Patent** (10) **Patent No.:** **US D1,003,238 S**
(45) **Date of Patent:** **** Oct. 31, 2023**

(54) **WIRELESS CHARGER**

(71) Applicants: **FOXCONN (KUNSHAN)
COMPUTER CONNECTOR CO.,
LTD., Kunshan (CN); FOXCONN
INTERCONNECT TECHNOLOGY
LIMITED, Grand Cayman (KY)**

(72) Inventors: **Duo Yang, Kunshan (CN); Jiang
Zhang, Kunshan (CN)**

(73) Assignees: **FOXCONN (KUNSHAN)
COMPUTER CONNECTOR CO.,
LTD., Kunshan (CN); FOXCONN
INTERCONNECT TECHNOLOGY
LIMITED, Grand Cayman (KY)**

(**) Term: **15 Years**

(21) Appl. No.: **29/811,087**

(22) Filed: **Oct. 11, 2021**

(30) **Foreign Application Priority Data**

Apr. 15, 2021 (CN) 202130212310.0

(57) **CLAIM**

The ornamental design for a wireless charger, as shown and described.

DESCRIPTION

FIG. 1 is a perspective view of a wireless charger showing our new design;

FIG. 2 is a front elevational view of the wireless charger;

FIG. 3 is a rear elevational view of the wireless charger;

FIG. 4 is a left side elevational view of the wireless charger;

FIG. 5 is a right side elevational view of the wireless charger;

FIG. 6 is a top plan view of the wireless charger; and,

FIG. 7 is a bottom plan view of the wireless charger.

1 Claim, 7 Drawing Sheets
